DESIGN.

—o—
O. UNZICKER.

SLEIGH BODY.

No. 17,275.

Patented Apr. 19, 1887.

UNITED STATES PATENT OFFICE.

OTTO UNZICKER, OF CHICAGO, ASSIGNOR TO ADOLPH SHOENINGER, OF LAKE VIEW, ILLINOIS.

DESIGN FOR A SLEIGH-BODY.

SPECIFICATION forming part of Design No. 17,275, dated April 19, 1887.

Application filed February 23, 1887. Serial No. 228,612. Term of patent 7 years.

To all whom it may concern:

Be it known that I, OTTO UNZICKER, a citizen of the United States of America, residing at Chicago, in the county of Cook and State of Illinois, have produced a certain new and original Design for a Sleigh-Body, of which the following is a specification, reference being had therein to the accompanying drawing, forming part thereof.

10 The leading features of my design consist in the peculiar form of the front portion, of the runners, and of the braces or stays.

The photograph represents a perspective of the sleigh complete.

15 The peculiarly-shaped front portion or part of the sleigh-body is marked D, and is a combination of the seat and back portion, A B C c, by a downwardly-curved portion, d, which is extended into the upwardly double-curved part d', which latter is curved or bent inward toward the seat; and then at the top, which is

higher than the seat, it is curved outward, thus giving the form or appearance of a graceful double or ogee curve. A guard-rail, F, may be applied around the top of the part d', 25 and held at a little distance therefrom to show a space between it and the said part d'.

What I claim is—

1. In a design for a sleigh-body, a front, D, formed with a downwardly-curved portion, d, 30 and an upwardly double or ogee curved portion, d', substantially as described.

2. In a design for a sleigh-body, a front, D, formed of the curved portions d and d', as described, and back portion, A B C c, as shown 35 and described.

In testimony whereof I affix my signature in presence of two witnesses.

OTTO UNZICKER.

Witnesses:

WILLIAM H. LOTZ,
OTTO LUBKERT.
